(57) CLAIM

The ornamental design for a slice drum, as shown and described.

DESCRIPTION

FIG. 1 is a top perspective view of a slice drum showing our new design.

FIG. 2 is a bottom perspective view thereof.

FIG. 3 is a top plan view thereof.

FIG. 4 is a bottom plan view thereof.

FIG. 5 is a front elevation view thereof.

FIG. 6 is a back elevation view thereof.

FIG. 7 is a right side elevation view thereof; and,

FIG. 8 is a left side elevation view thereof.

The broken line in the figure drawings represents unclaimed environment only and forms no part of the claimed design.
